UNITED STATES PATENT OFFICE.

ALBERT EDGAR BLACKMAN, OF MOUNT VERNON, NEW YORK.

RADIATOR COVER.

Application filed November 21, 1925. Serial No. 70,576.

My invention relates to radiator covers in the form of a box which is adapted to be stood over and completely envelop a radiator of that class which is used for heating 5 rooms of buildings by steam or hot water. One of the principal objects of my invention is so to construct the cover that its cost of manufacture will be at a minimum and at the same time it will be ornamental in 10 appearance and of great strength. Another object is to provide the top or cap with insulating material to prevent air currents rising directly above the radiator and thereby causing a settlement of dust on the adjacent 15 wall and hangings. The insulation of the top also permits its use as a shelf on which ornaments or other objects can be stood. Other objects and advantages will become apparent from a further study of the specification and drawings in which:—

Fig. 1 is a front elevation of the cover with a portion of the perforated front panel and a portion of the front flange and cover cut away, Fig. 2 is a section taken along 25 the line 2—2 of Fig. 1, Fig. 3 is a section taken along the line 3—3 of Fig. 1, Fig. 4 is a top plan view of the cover with the cap and perforated front plate removed, Fig. 5 is a development of the sheet metal piece 30 forming the cap, Fig. 6 is a development of the sheet metal piece forming the back and shelf portion and Fig. 7 is a development of the sheet metal portion forming the sides.

The sheet metal piece 8, shown developed in Fig. 6 is folded into the shelf 9 and barrier 10. Heat insulating material 24 such as asbestos, is placed on shelf 9. The sheet metal piece 11 shown developed in Fig. 7 forms one side of the radiator cover. A similar piece is used for the other side. Piece 11 is bent into side flanges 12 and top flange 13. The bent side pieces 11 are welded to back 8 at the rearward flanges 12 as seen in Fig. 4. A cross bar 14, which extends across the lower front of the radiator cover, is welded at its ends to the sides of flanges 12 and lies in the same plane with them. Guide angles 15 are welded to sides 11 just far enough behind flanges 12 to give clearance for the insertion of the perforated front plate 16. Plate 16 is formed with a bottom flange 17 and an upper flange 18. The sheet metal piece 19 forming the cap piece, shown developed in Fig. 5, has a lip 20 folded into a front loop portion (Fig. 2) and lips 21 folded into side loop portions

(Fig. 1). Lip 22 is folded down to form a back flange (Fig. 2) which is adapted to be welded to rear flanges 12 of side pieces 11. Curved deflector plate 23 is welded to back 60 8 and to the underside of cap 19.

With the cover completely welded together, plate 16 is inserted up from the bottom, front loop 20 of cap 19 being sprung forward a sufficient amount to permit flange 65 18 of plate 16 to clear it on its way up.

Legs 23 are welded to the four lower corners of the radiator cover.

Features of the radiator cover shown herein, but not claimed, form the subject matter 70 of my co-pending application, Serial No. 747,228, filed Nov. 1, 1924.

I claim:—

1. A radiator cover having a sheet metal back and sides, an apertured front panel, 75 a cap fitting upon said back and sides, said back being bent forward at its upper end to form a shelf, said shelf being located a substantial distance down from the under side of said cap, and a deflector plate fastened near one end to the vertical portion 80 of the back and near the other end to the under side of said shelf.

2. A radiator cover having sheet metal back and side portions, an apertured front 85 panel and a cap for covering the top of said cover, said cap having a substantially channel shaped overhang at its forward end, the front panel being provided with an outwardly extending flange lying within said 90 channel shaped overhang.

3. A radiator cover having sheet metal back, top and sides rigidly attached to each other, a cap for covering the top of said cover, and an apertured front panel slidably set in position upon said sides, said back turning forward at its upper end to form a shelf, the forward end of the shelf turned upward to form a barrier, the outside face of said barrier coming substantially adjacent the inside face of the upper end of the front panel, said shelf being located a substantial distance down from the underside of said cap leaving a space under the cap, and insulating material placed upon said shelf in said space, the back of said cap being adapted to close up the rear of said space.

4. A radiator cover having sheet metal back, top and sides rigidly attached to each other and an apertured front panel slidably set in position upon said sides, said

back turning forward at its upper end to form a shelf at a substantial distance below said top to provide a space, insulating material placed upon said shelf, and means for closing up the rear of said space above the back for retaining said material in place.

5. A radiator cover having sheet metal back and sides, an apertured front panel, a cap fitting upon said back and sides, said 10 back being bent forward at its upper end to

form a shelf, said shelf being located a substantial distance down from the under side of the top wall of said cap, and insulating material placed upon said shelf in the space left between the top wall of the cap and 15 the shelf, the back of said cap extending downward from said top wall for closing up the rear of said space.

ALBERT EDGAR BLACKMAN.
